F. C. McCullough Inventor

By C. Shaw & Co. Attorney

UNITED STATES PATENT OFFICE.

FRANK C. McCULLOUGH, OF COSHOCOTON, OHIO.

CHIN SUPPORT.

Application filed July 1, 1920. Serial No. 393,312.

To all whom it may concern:

Be it known that I, FRANK C. McCULLOUGH, a citizen of the United States, residing at Coshocton, in the county of Coshocton and State of Ohio, have invented a new and useful Chin Support, of which the following is a specification.

By way of explanation it may be stated that when the chin of a corpse is supported by an ordinary prop, extended between the chin and the chest, a number of disadvantages present themselves. For instance, if the corpse has chin whiskers, the whiskers, obviously, are disarranged by the prop. A common chin prop often leads to the production of a disfiguring mark on the chin, notwithstanding the expedients known in the undertaker's art. Often, an undertaker desires to shift the position of the trunk, and such a shifting cannot take place, without taking away the support for the chin, if the chin is sustained by a prop extended between the chest and the chin.

Broadly considered, it is the object of this invention to provide a chin support which, in operation, will present none of the disadvantages enumerated above.

It is within the province of the disclosure to improve generally and to enhance the utility of, devices of that type to which the invention appertains.

One form of the invention is shown in the drawing, by way of illustration, but it is to be understood that, within the scope of what is claimed, a mechanic may make changes falling within his skill, without departing from the spirit of the invention or rendering the article of no utility.

In the drawings:—Figure 1 shows, in end elevation, a device constructed in accordance with the invention, mounted upon a head rest and sustaining the jaw of a corpse; Figure 2 is a front elevation wherein parts appear in section; Figure 3 is an elevation showing a slight modification in the jaw support.

In carrying out the invention there is provided a member 1, shaped as indicated at 2 to form arms 3 which, preferably, are approximately parallel. The intermediate por-

tion of the member 1 is connected in any suitable way, as shown at 4, to a base plate 5. The arms 3 are tubular, props 6 being longitudinally adjustable therein, the props being supplied at their upper ends with inclined cup-shaped heads 7. Set screws 8 are threaded into the arms 3 and engage the props 6, to hold the props in adjusted positions.

In practical operation, the member 1 is placed astride the neck of a corpse, the base plate 6 being supported on the rest 9 which carries the head of the corpse, the members 7 engaging the jaw below the ears and at the angles of the jaw. The set screws 8 may be loosened, and the props 6 may be raised and lowered, so as to engage properly with the angles of the jaw. When an adjustment in the distance between the props is desired, the prop 6^a of Figure 3 may be used, the prop being offset as shown at 10, so that the head 7^a is set inwardly. Clearly, when the distance between the angles of the jaw, measured transversely, is not great, the prop shown in Figure 3 may be used instead of the prop shown in Figure 2. Further, one of the props shown in Figure 3 may be used with one of the props shown in Figure 2.

The device forming the subject matter of this application is so constructed that it will leave no mark on the chin. Since the device does not engage the chest of the corpse, the trunk may be shifted without taking away the support for the chin. It will be obvious, from an inspection of Figure 1, that if the corpse should happen to have chin whiskers, the whiskers will not be disarranged when the jaw is supported by the device shown. The prop at one side may be raised or lowered independently of the prop at the other side, and by this operation, the head of the corpse can be turned as occasion may demand.

I claim:—

In a device of the class described, a base plate and a pair of spaced jaw props adjustable on the base plate at an angle thereto, the jaw props constituting the sole projections on the base plate, and the base plate

being sufficiently narrow so that it may be placed beneath the neck of a corpse, and be adjusted longitudinally of the neck of a corpse, whilst the shoulders of the corpse and the head of the corpse rest upon a head board, independently of the base plate.

5 In testimony that I claim the foregoing

as my own, I have hereto affixed my signature in the presence of two witnesses.

FRANK C. McCULLOUGH.
